United States Patent Office

Des. 208,083
Patented July 11, 1967

208,083

ELECTRIC KNIFE HANDLE

Jerold R. Peterson, Roselle, Ill., assignor to Sunbeam Corporation, Chicago, Ill., a corporation of Illinois

Filed Dec. 27, 1966, Ser. No. 5,181

Term of patent 14 years

(Cl. D95—3)

Fig. 4.

Fig. 5.

Fig. 6.

FIG. 1 is a front perspective view of an electric knife handle embodying my new design, the broken line showing of the knife blade being for purposes of illustration only;

FIGS. 2 and 3 are rear and front elevational views respectively on an enlarged scale thereof;

FIG. 4 is a top plan view thereof;

FIG. 5 is a side elevational view thereof; and,

FIG. 6 is a bottom plan view thereof.

I claim:

The ornamental design for an electric knife handle, as shown and described.
